PNEUMATIC MATTRESS AND THE LIKE

Robert W. Sampson, New York, N. Y., assignor
to Charles J. Hardy, New York, N. Y.

Application November 23, 1933, Serial No. 699,328

7 Claims. (Cl. 5—348)

My invention relates to mattresses, cushions and the like which embody a pneumatic element or elements in combination with textile and/or fibrous elements all of which may be assembled 5 in a complete composite unit.

Objects of my invention are to give to the pneumatic element or elements a configuration which will increase the efficiency thereof; to counteract any tendency toward undue local 10 yieldability in the pneumatic element, or the formation of objectionable depressions or elevations therein when in use; to increase the efficiency of the pneumatic element and of the mattress by an improved method of assembling 15 the pneumatic element between flexible, textile and/or fibrous elements of different degrees of softness or yieldability; to produce a reversible mattress which shall be of different degrees of softness on its opposite sides; to form a mattress, 20 embodying a plurality of pneumatic elements, which may be folded up compactly without doubling or bending a pneumatic element on itself.

In the drawings, in each of the figures of 25 which similar reference letters refer to similar parts, Figure 1 is a perspective view of the improved pneumatic element, top up; Figure 2 is a perspective view of the same, bottom up; Figure 3 is a longitudinal sectional view, on an enlarged 30 scale, of one pneumatic element with its associated textile and fibrous topping and base, and the covering, taken as on a line 3—3 of Figure 4, which is a perspective view of a typical mattress, bottom up, and with the foundation and cover 35 partially broken away, this view being on a reduced scale as compared with Figures 1 and 2; Figure 5 is a perspective view of a detail of a corner of the mattress, on a scale similar to that of Figures 1 and 2; Figure 6 is a plan view of a 40 mattress adapted to fold up on itself; Figure 7 is a longitudinal view of the same taken as looking up on Figure 6; Figure 8 is a plan view of an improved mattress support; Figure 9 is an end view of the same; Figure 10 is a longitudinal view 45 of a complete mattress, mounted on the improved support which is shown as a longitudinal section taken on the line 10—10 of Figure 8; and Figure 11 is an edge view of a modified form of pneumatic element having a stiffened marginal 50 bead or rim, the upper right hand corner being in section, better to show the construction. This figure is on the same scale as Figure 3. Figures 6, 7, 8, 9 and 10 are on a reduced scale as compared with Figure 4.

55 The topping element 1 of the mattress is shown

as composed of a fibrous body 2 of hair, vegetable fibre or the like, inclosed within a suitable cover 3, and adapted to yield locally, both by compression and depression, when pressed from above.

The foundation or bottom element 4 is composed of a similar, but preferably less soft and yieldable, fibrous body 5, inclosed in a suitable casing 6, and is preferably less flexible and yieldable than the topping 1.

Between the topping 1 and foundation 4 is inserted the pneumatic element or elements 7. It is desirable, especially for full length mattresses, to use a plurality of these pneumatic elements, for instance 3, as shown in Figure 4, both for facilitating manufacture, convenience of removal and replacement, and for making the mattress conveniently foldable as hereinafter pointed out.

Each of these elements 7 is shown as consisting of a single, integral unit adapted to retain within it confined air, and having on what is normally its lower or under side a plurality of elongated chambers 8, 8, each provided with a plurality of arched recesses 9, 9, springing lengthwise thereof, and with a resulting, plurality of protuberances 10, 10, between and beyond the recesses, so that, when the element is laid with the chambers 8, 8 down, it will be supported by the protuberances 10, 10.

The upper face of the element 7 is formed with a plurality of diagonally disposed ribs or ridges 11, 11, forming between them depressions 12, 12, the bottoms of which, when they cross above the depressions between the elongated chambers 8, 8 are formed of a single thickness of material, and preferably have perforations 14, 14, through that single thickness to facilitate ventilation. Those familiar with the art will understand that a mattress core of this character is, preferably, formed by using two sheets of unvulcanized rubber, which are drawn into the desired form for the top and bottom, respectively, of the core, and are then assembled and vulcanized to each other. And that where the bottoms of the depressions 12, 12 cross the bottoms of the depressions 13, 13, those parts of the bottoms of the respective depressions will lie against each other and, when vulcanized, will coalesce in a single united thickness or layer. The perforations 14, 14 pass through the coalesced layer 50 from side to side.

Where the ridged air chambers 11, 11 cross the elongated chambers 8, 8, they open into each other, so that inclosed air may move to and fro through all of them and may be displaced by 55

pressure from one area and made to increase the air pressure at other points.

By disposing the upper air channels diagonally of the lower ones a material improvement is obtained in the functioning of the air container in use as a mattress or cushion element, in comparison with a construction in which the upper and lower air chambers are disposed at right angles to each other; for tendency of the container to bend or buckle along right lines is counteracted, and more uniform support for such a load as the human body is obtained. For instance, if a user lies extended, from end to end of a container having top and bottom air chambers disposed at right angles to each other, the lower limbs, being parallel to the lower air chambers, will tend to bed down between them, or to be carried by the chamber or chambers substantially adjacent to or parallel with them, the upper chambers pressing down, only to the extent of their breadth, against the lower chambers. But where a diagonal disposition of the upper chambers is adopted the pressure of each upper chamber will be spread over a greater area of the lower chamber, and a more uniform support for the load will result, without the loss of softness or resiliency; and the container will tend to retain an approximately flat disposition, with diminished liability to fold or buckle along right lines.

Furthermore, if in a sectional mattress, such as is shown in Figure 4, the diagonal chambers of one section slope in a different direction from those of the next one, for instance from right to left, as shown in Figure 1, in one section, and from left to right in an adjacent section, which may be accomplished by turning the second section end for end, a further diffusion of support will be obtained, and the carrying quality of the mattress will be further improved.

The carrying quality of the mattress is also improved by the placing of the pneumatic element between the topping 1 and the yielding foundation 4. Because the comparatively soft topping affords a locally yielding carrier in which the more prominent irregularities of the human body may bed down before transmitting their weight to the pneumatic element, the pressure upon which will be more diffused and uniform than it otherwise would be. The topping, also, will press somewhat into the depressions 12, 12, still further spreading the load.

When pressure is placed upon the mattress it will be borne first by the protuberances 10, 10 on the under side of the pneumatic element, the arches between which will tend to resist a tendency of the chambers 8, 8, to flatten out, the protuberances 10, 10 collapsing somewhat, and bedding somewhat into the foundation 4, before the arched portions of the chamber 8 are pressed down to that foundation. Thus an increasing resistance is built up out of the support of the protuberances, the carrying capacity of the arches and the gradual yielding of the foundation, all of which cooperate to produce an approximate uniformity of softly yielding support, particularly in combination with the diagonal top chambers and the soft topping as already described.

By turning the mattress over a firmer upper surface may be presented for use, if that is desired.

It is convenient to assemble the elements of the mattress within a suitable cover 15, which, preferably, may be readily closed and opened along one side, as by the use of a zipper attach-

ment 16, thus permitting the insertion or removal at will of the inclosed elements of the mattress for airing, cleaning and repair. This arrangement also facilitates access to the pneumatic valves 17, 17, for the proper regulation of the air in the elements 1, 1.

If it is desired to fold the composite mattress, an arrangement may be adopted which will readily permit this by making the topping and foundation in sections similar in size to the pneumatic 10 section and forming the cover 15A with several pockets for instance three, into each of which a topping, air container and foundation are inserted, the pockets being preferably joined to each other at their adjacent edges, alternately at top 15 and bottom, as at 18, 19, so that one end section may be folded over and the other under the middle section; thus permitting the sections of the mattress to be folded flat-wise against each other.

Under certain conditions, for instance where 20 the mattress is to be used to replace one supported by box springs, it is desirable to provide a suitable, convenient support for it. And such a support is shown in Figures 8, 9 and 10, wherein a flat top 20, of ply board or other suitable material, is carried by cross members 21, 21, stayed by edgings 22, 22. The top 20 is perforated, as at 23, 23, for the purpose of ventilation. Such a support may be placed within an ordinary bedstead frame, and will provide a suitable carrier 30 for the mattress.

Proper ventilation is an important consideration in mattresses; as both for sanitation and comfort access of air to the interior of the mattress is desirable.

The construction of my improved mattress insures adequate ventilation, not only through the topping 1 and foundation 4, but also through the perforations 14, 14, the depressions 12, 12, the recesses 9, 9, and the spaces 13, 13 between the 40 chambers 8, 8, all of which will be more or less open during both use and disuse of the mattress and which will cooperate bellows-like to expel and draw in air through apertures 27, 27 in the casing as the mattress is subjected to varying pressures 45 and modifications of form during use.

In Figure 11, I have shown a modification of the marginal rim or bead of the pneumatic element, which is substantially thickened as compared, for instance, with the showing of Figure 3 of the 50 drawings, and is preferably moulded so as to produce a flat top with an underside sloping downwardly and inwardly at an angle of about 45 degrees from the top. The result of this construction is to surround the pneumatic element with 55 a comparatively stiff rim 25, which will quite definitely support the cover or casing against deflection inwardly, and will materially assist in maintaining the proper contour of the mattress or cushion.

By means of my improvement I produce a mattress embodying the advantages of both an air confining element or elements and of textile and fibrous elements, the desirable characteristics of one element supplementing those of the others so as to result in a unitary assembly quite uniform in softness, yieldability and resilience, susceptible of being made harder or softer by varying the air control of the pneumatic element, automatically ventilates itself when in use, retaining its 70 form without permanent distortion, and which may be conveniently folded upon itself if desired.

The particular embodiment of my invention which I have illustrated and described is to be taken as a typical and not on exclusive form; for 75

details may be varied, as by the use of equivalents, without departing from the spirit of my invention or the scope of the claims.

Having thus described my invention, what I claim and desire to secure by Letters Patent of the United States is:—

1. A pneumatic mattress or cushion, composed of rubber or the like, embodying a plurality of elongated air chambers projecting from one face 10 and extending across the mattress, each provided on its outer face with a plurality of medial and terminal protuberances with arches springing longitudinally inwardly between them, in combination with a thickened, flexible, textile and fibrous foundation sufficiently resistant to substantially oppose the bedding down therein of the aforesaid protuberances, and a flexible, textile and fibrous topping, softer and thicker than the foundation, and disposed on the opposite side of 20 the air container from the foundation.

2. In a pneumatic mattress or cushion, the combination of an element composed of rubber or the like, and embodying a plurality of elongated air chambers projecting from and extending across 25 one face thereof and each provided on its outer face with a plurality of medial and terminal protuberances with arches springing longitudinally inward between them, another plurality of inter-communicating air chambers forming ridges projecting from the other face of the air container and disposed diagonally relative to the first mentioned chambers, a thickened, soft, textile topping resting against the diagonal chambers, and a thickened, but comparatively stiffer, flexible, 30 textile foundation applied against the opposed series of chambers, and means for holding the aforesaid elements in assembled relation.

3. A pneumatic mattress or cushion, composed of rubber or the like, embodying a plurality of 40 elongated air chambers projecting from one face and extending across the mattress and each provided on its outer face with a plurality of medial and terminal protuberances with a plurality of arches springing longitudinally inwardly between 45 them, and a plurality of intercommunicating air chambers projecting from its other face and disposed diagonally relative to the first mentioned chambers.

4. The combination in a mattress of a pneumatic core having a series of comparatively deep trough like depressions each extending from 50 within one edge to within another edge of one face thereof, and another series of comparatively deep trough like depressions each extending 55 across the opposite face of the core within its edges with their longitudinal axes offset angularly from those of the first mentioned series, the bottoms of the opposed depressions being separated by comparatively thin integral webs, ventilating openings passing through said webs and forming channels interconnecting a plurality of 60 said depressions, and a textile facing for each side of the core, the depth of the depressions being sufficient to prevent the textile facings 65 from reaching their bottoms in the normal use

of the mattress, whereby series of permanently free and relatively crossed interconnected, ventilating channels are maintained in the opposed faces of the core.

5. The combination in a mattress of a pneumatic core having a series of trough like depressions with closed ends each extending from one edge to another of one face thereof, and another series of trough like depressions extending across 10 the opposite face of the core with their longitudinal axes offset angularly from those of the first mentioned series, the opposed depressions at their points of crossing extending through the whole thickness of the core except that their bottoms at the points of crossing are separated by comparatively thin integral webs, ventilating openings passing through said webs and forming 15 ventilating channels interconnecting a multiplicity of said depressions, and a textile facing for each side of the core, the depressions being sufficiently deep and narrow to prevent the textile facings from reaching their bottoms in the normal use of the mattress, whereby series of permanently free and relatively crossed and interconnected 20 ventilating channels are maintained in the 25 opposed faces of the core.

6. The combination in a mattress of a pneumatic core having a series of elongated depressions with abrupt sides each extending across one face thereof the ends of the depressions being closed by an integral rim having a continuous and acute angled outer edge, and another series of elongated depressions with abrupt sides each extending across the opposite face of the core 30 with their longitudinal axes offset angularly from and crossing a plurality of the first mentioned series of depressions, the opposed depression at their points of crossing extending through the whole thickness of the core except that their bottoms at the point of crossing are separated by comparatively thin integral webs, ventilating 35 openings passing through said webs and connecting each depression with a plurality of opposed depressions, and a textile facing for each side of the core, the depressions being sufficiently deep and narrow to prevent the textile facings from reaching the bottoms of the depressions in the normal use of the mattress, whereby series of 40 permanently free and relatively crossed ventilating channels are maintained in the opposed faces 45 of the core.

7. A new article of manufacture, a rectangular, pneumatic mattress or cushion core, having a series of trough like depressions extending across the bottom thereof, another series of trough like depressions extending across the top thereof with their longitudinal axes angularly offset from those of the first mentioned series, and a comparatively stiff, but flexible, integral 55 marginal rim having an outwardly extending, angular, upper edge surrounding the upper edge of the core in the plane of its top and closing the ends of the depressions in its top.

ROBERT W. SAMPSON. 65
